UNITED STATES PATENT OFFICE.

HEBER C. INSLEE, OF ROSELLE, NEW JERSEY, ASSIGNOR TO THE BABCOCK & WILCOX COMPANY, OF BAYONNE, NEW JERSEY, A CORPORATION OF NEW JERSEY.

STEAM-SUPERHEATER.

1,200,357.

Specification of Letters Patent. Patented Oct. 3, 1916.

Application filed July 28, 1915. Serial No. 42,259.

To all whom it may concern:

Be it known that I, HEBER C. INSLEE, a citizen of the United States, residing at Roselle, in the county of Union and State of New Jersey, have invented certain new and useful Improvements in Steam-Superheaters, of which the following is a specification.

My invention relates to steam superheaters and more particularly to an engaging or locking piece for holding a core in place within the superheater tube. This feature of the invention, and others, will be understood by reference to the accompanying drawings, in which—

Figure 1 is a section through a superheater tube showing the core in elevation; Fig. 2 an enlarged section of the tube and core, broken away, and part of the core being in elevation; Fig. 3 a transverse section on the plane of the line 3—3 of Fig. 2; Fig. 4 a view of a spacer which surrounds the core, the tube being shown in broken lines; Fig. 5 a section on the plane of the line 5—5 of Fig. 4; Fig. 6 a section on the plane of the line 6—6 of Fig. 2; Fig. 7 a section on the plane of the line 7—7 of Fig. 6; and Fig. 8 an end view of the locking device.

Similar reference numerals indicate similar parts in the several views.

In the drawings the numeral 1 designates a U-shaped superheater tube the ends of which are expanded into boxes 2 and 3, said boxes having hand-hole fittings as usual. The cores 4 are cylindrical and extend from the lower ends of the tube throughout substantially their straight portions. For the purpose of holding each core in position, I have devised a locking piece adapted to surround the lower end of the core and to be forced into the space between the core and the lower end of the tube. In the form shown this locking piece consists of a ring 5 having a series of fingers 6 projecting therefrom. The inner faces of these fingers, at their upper ends, are beveled to correspond substantially with the tapered surface 7 of the lower end of the core. Said fingers are of such width that, when forced between the lower end of the core and the end of the tube, they will be wedged tight and thus hold the core securely in position. Any suitable means may be used to force the locking device into position. For such

purpose I have used a nut 8 placed on the threaded end of the core and bearing against the side of the ring 5. The fingers 6 are provided with lateral projections 9 to limit their inward movement by contacting with the end of the tube rolled out by the expander. The core is shown as made up of hollow or tubular sections having their ends 10 reduced and exteriorly threaded to receive a coupling sleeve 11. At the ends of each section are triangular-shaped spacing pieces 12 having a central opening by which they may be placed over the sections. These pieces serve to center the core in the tubes. The upper end of the core is reduced in diameter and the core closed by a cap 13 which cap also serves to hold one of the spacing pieces 12 in position. The locking piece which is forced into the space between the core and the lower end of the tube holds the tube firmly in a central position and does not require a groove to be rolled in the tube as in other forms of locking devices. By bearing against the interior of the tube at the point shown, there is no danger of distorting the tube, which is reinforced at this point by the superheater box. A further advantage of the device is that by employing it a core can be readily removed and replaced due to the taper. Again, the device does not interfere with the hand-hole fittings opposite the tubes which can be readily removed and replaced without manipulating the core.

What I claim and desire to secure by Letters Patent of the United States is:—

1. In combination, a superheater tube, a core therein having its lower end tapered, and a wedge device for supporting the core consisting of a base having fingers projecting therefrom, said fingers being adapted to be forced into the space between the core and the lower open end of the tube.

2. In combination, a superheater tube, a core therein, said core having its lower end tapered, and a wedge having a corresponding face adapted to be driven into the space between the core and the lower open end of the tube.

3. In combination, a superheater tube, a core therein having its lower end tapered, a wedge device for supporting the core adapted to be forced into the space between the core and the lower open end of the tube, said

wedge device having projections adapted to engage the lower edge of the tube to limit its movement.

4. In combination, a superheater tube, a core therein, a wedge device for supporting the core comprising a ring surrounding the lower end of the core with fingers projecting therefrom, said fingers being adapted to be forced into the space between the core and

the lower open end of the tube, and a nut ¹⁶ for forcing said fingers into said space.

In testimony whereof I have hereunto signed my name in the presence of two subscribing witnesses.

HEBER C. INSLEE.
